UNITED STATES PATENT OFFICE.

HENRY F. GEIGER, OF LOVELAND, OHIO, ASSIGNOR OF ONE-HALF TO WALTER R. RAUCK, OF CINCINNATI, OHIO.

CONTAINER.

Application filed October 17, 1923. Serial No. 669,177.

To all whom it may concern:

Be it known that I, HENRY F. GEIGER, a citizen of the United States, and a resident of Loveland, in the county of Hamilton and State of Ohio, have invented certain new and useful Improvements in Containers, of which the following is a full, clear, and exact description, reference being had to the accompanying drawings, forming part 10 of this specification.

My invention relates to containers or kegs, particularly of a type to act as shipping packages and containers for various materials, bodies, such as nails and like objects.

15 The effort to provide containers capable of shipment in a knockdown condition, and so as to permit the use of metal in its construction, which is cheaper than wood, has brought forth a number of devices, none of 20 which to my knowledge is as simple, effective and easy to make and use, as the device of my invention.

It is my object among other things to provide a simple seamed sheet of metal to act 25 as the body of the barrel, and to provide for a chime at either or both ends thereof, in combination with an improved means for removably mounting a head in each chime, preferably in a manner which permits its 30 ready removal, the device, together with a simple means of removing the desired head, for use of the keg contents.

These objects I accomplish by that certain construction and arrangement of parts to be 35 more specifically pointed out and claimed.

In the drawings:

Figure 1 is a perspective view of one form of my device.

Figure 2 is a section on the line 2—2 of 40 Figure 1.

Figure 3 is a section on the line 3—3 of Figure 1.

It will be noted that my barrel body is 45 formed of a piece of sheet metal 1, formed except at the two ends with a simple seam of folds 2, 3, so that in setting up the barrel the sheet can be bent into a circle, the folds hooked into each other and a pressing operation applied to flatten down and tightly 50 secure the seam.

In the preferred construction of container both ends of the body of the barrel or container and the heads therefor are similarly formed and constructed, but in some instances it may be desirable to provide my

improved form of construction at one end only. At each end, the sheet 1 is formed with a particular form of fold. In the first place there is formed a peripheral bead 4 having an outwardly curved wall, and a base 5, facing to the center of the body. The metal extends beyond the bead 4 to form an outer chime wall 4^a and is then turned inwardly of the sheet at the ends as at 6, in a well rounded fold line, and extended inwardly to 60 form a wall 6^a within the body concentric thereto and provide an inner chime wall 4^b spaced from the chime wall 4^a. At 7, the wall 6 is beaded peripherally, in like manner to the bead first mentioned in line therewith 65 for a purpose which will later appear.

From the foregoing description, it will be seen that I provide a bead and a groove, one carried by the body and the other carried by the flange, and preferably dispose 70 them in the same plane to enable the head to be simplified in its construction.

The top and bottom heads of the barrel are not shown as the same, although they 75 may be interchangeable, if desired. Each 80 head comprises a body portion 9, preferably bent on concentric lines to form an annular recess 10 and a flange 11, the depth of which is preferably equal to the length of the inwardly extending wall 6. The flange 11 is 85 adapted to enter the space between the body of the container and the wall 6, the latter being so disposed that the flange 11 will have a relatively close sliding fit between 90 these walls. 12 indicates an outwardly 95 curved portion formed in the flange 11 to provide a bead and a groove arranged to register and interlock with the groove 4 and bead 7 provided on the body 1 and flange 6, respectively, whereby the head will be removably secured in position.

From the foregoing description it will be seen that the head for the barrel is positioned by a movement from a point within the barrel outwardly against an annular wall, which being continuous and unbroken circumferentially prevents the loosening of the head in the chime as a result of the contents of the barrel being forced against the head due to a dropping of the barrel; at the same time the head is removably held in position and may be pushed inwardly by the application of force without damaging the walls of the chime or head.

In shipping the kegs, the sheets may be 110

readily nested, in a half round shape, and the heads shipped nested also. The top heads will preferably have a central formed up portion 13, which is dented in at the sides 5 as at 14 to form a handle, without forming any opening into the kegs.

In setting up the kegs for filling, the sheets 1 are first formed into seamed tubes, as has been noted. The one head is then 10 dropped into a tube, and pushed down with a tamping tool of any kind, so that the flange of the head will enter between the in-turned portion and the side of the tube, formed as described. The beaded portion 15 of the head flange will lie when in place in registry with the two beads on the end portions or chime portions of the tubular member.

A simple expansion tool of any kind may 20 then be applied to the said chime walls, and the parts forced together, closing in the loosely turned-in portion or chime wall 4^b about the flange on the lid, and closing the rounded point at 6. This rounded portion 25 braces the edge of the keg during shipment, and during the filling operation, and is substantially flattened out when the head is in the barrel, giving the edge a double brace.

The keg is then filled, and as in usual 30 practice, the nails, screws, bolts, nuts or the like articles, for which these kegs will be used are weighed and dumped into the kegs. By a jarring on the keg they will settle down at the top, leaving ample space for 35 inserting the top head. If suitable space is not left in practice by filling up and jarring down, some means must be adopted for regulating the filling to permit of the insertion of the head.

40 The keg being filled, the top head is then dropped in, with its flange upwardly, and pushed down past the inturned edge of the keg chime, and finally lifted up by the handle until the head flange snaps into bead 45 registering position in the chime, with the head flange between the body and in-turned edge, as in the case of the bottom head. The parts are then expanded out-

wardly again, forcing the lid flange, inner chime portion, and outer chime portion together firmly and permanently against any chance dislodgment.

The keg so formed and filled will have practically no point exposed to passage of moisture, as all joints will be seamed and tight. To remove the top head, it will be tapped down at four or five points, to work the inner flange of the chime away and release the interlocking condition at the beads. If the head has room to be introduced in the first place, it can be removed in a like manner, but a chance jar will not dislodge it; nor will a bad dent, if such should take place, make it loose in its position. Thus upon tapping loose the beaded connection, 65 the head can be driven down into the keg, and lifted out.

The chime portions of the keg will have two thicknesses of the main body and the interlying thickness of the head flange, at 70 all points, which will form a very strong chime, well reinforced in stiffness by the beads. The sheet 1 may be of corrugated metal, if desired, although my opinion is that the plain metal will do just as well.

Having thus described my invention, what I claim as new and desire to secure by Letters Patent, is:—

1. A metal container having inturned flanges at the ends, each end of the body and each inturned flange being provided with a groove and a bead, respectively, and heads for the container provided with flanges each having a bead and a groove adapted to interlock with those first mentioned when the heads are moved into closing position.

2. A metal container comprising a body having an inturned flange at one end, said body and flange being provided with a groove and a bead, respectively, and a head having a flange adapted to fit between the body and its inturned flange and provided with a bead and a groove adapted to interlock with those first mentioned when the head is moved into closing position.

HENRY F. GEIGER.
